UNITED STATES PATENT OFFICE.

STORY B. LADD, OF WASHINGTON, DISTRICT OF COLUMBIA.

LIQUID-AIR CANDLE.

Application filed October 31, 1924. Serial No. 746,966.

To all whom it may concern:

Be it known that I, STORY B. LADD, citizen of the United States, residing at Washington, District of Columbia, have invented 5 certain new and useful Improvements in Liquid-Air Candles, of which the following is a specification.

The present invention relates to cooling devices and particularly to a liquid air or 10 gas cooling device.

An object of the invention is to provide a liquid air or gas container having means associated therewith for conserving the supply of liquid air or gas therein.

Another object of the invention is to provide a liquid air or gas container having an evaporating surface associated therewith.

A further object of the invention is to 20 provide a liquid air or gas container having an evaporating surface in capillary communication with the interior of said container and which is adapted to protrude therefrom, with means for regulating the extent to which said evaporating surface protrudes.

Still further objects of the invention are to provide a container and evaporating surface of the character stated, with means for covering and exposing said evaporating surface, and means for exposing said surface 30 and creating a current of air or gas thereacross.

Other objects and advantages of the invention will appear in the following detailed description thereof, taken in connection 35 with the accompanying drawings, which illustrate by way of example, a preferred embodiment thereof, but which are not to be taken as a definition of the limits of the invention, reference being had to the appended 40 claims for that purpose.

In the drawings:

Fig. 1 is a vertical sectional view through a container and evaporating surface embodying the present invention;

Fig. 2 is a horizontal section taken on the line 2—2 of Fig. 1;

Fig. 3 is a vertical sectional view through a cabinet containing a preferred form of container and evaporating surface associated 50 with means for setting in motion the air or gas evaporating therefrom;

Fig. 4 is a horizontal sectional view taken on the line 4—4 of Fig. 3;

Fig. 5 is a detail view showing the controlling device.

Fig. 6 is a top plan view of a modified

form of liquid air or gas candle embodying the present invention.

Fig. 7 is a side elevation thereof.

Referring in detail to the drawings, a container 9 is provided with an interior portion 10, adapted to contain liquid air or gas. A series of openings 11 are provided at the top thereof to permit escape of evaporated air or gas. The openings 11 form a communicating medium between the interior of the container, and a chamber 12 formed by the concentric walls 13 and 14. At the bottom of the wall 14 is an opening 15, forming a communicating means between the chamber 12 and the space 16. The space or chamber 16 is in communication with the atmosphere through a series of openings 17, preferably provided near the top thereof.

A vacuum or other insulating chamber 18 may surround the container.

At its top the container 9 is formed with a neck 19, which is internally screw-threaded for the reception of an externally screw-threaded closing member 20, which is provided with an opening therethrough for the reception of a member 21, which protrudes above the closure 20 at one end and has its other end extending down to the bottom of the interior of the container. The member 21 is preferably in the form of a wick, and thus has its upper or evaporating surface in capillary communication with the liquid air or gas in the lower part of the container.

A device may be provided for regulating the extent to which the evaporating surface protrudes above the closure member 20 and in the drawings is illustrated as having the form of a wire 22 extending through the closure member 20 and gripping the wick 21 at its upper and lower ends 23 and 24, which are shown as encircling said wick. A loop 25 may be formed intermediate the ends of the raising and lowering member 22 to form a convenient handle therefor. The closure member 20 may be formed hollow and filled with insulating packing material, as shown.

The container 9 may be formed with a lug 26, adapted to receive a hinge pin 27, upon which the top 28 of the container is shown as being mounted. The top is preferably formed with an interior opening 29 and exterior openings 30, and has the intermediate wall 31 therein to provide a tortuous passage for the escape of evaporated air or gas.

Referring now to Figs. 3, 4 and 5, a cabi-

net 41 is provided with openings 42 and 43, through which a current of air is adapted to be drawn into the cabinet and expelled therefrom. Each of these openings is preferably 5 provided with any desired form of screen 44. The container 9 is placed within the cabinet 41 and is retained in position therein by means of flanges 45 on the floor of the cabinet.

10 A fan 46 and fan motor 47, or other means for creating a current of air or gas, are mounted within the cabinet 41. The fan is controlled by a switch 50, which preferably takes the form of a rheostat having a plurality of stationary contact members 51, and a pivoted arm 52 having the movable contact member 53.

15 Slidably mounted in one of the cabinet walls is a controlling member 56, which is illustrated as having the form of a rod provided at its outer end with a knob 57 or other convenient form for manual operation. At its inner end the rod 56 is bent at right angles, as shown at 58, and extends into and 20 through a longitudinal slot 59, formed in the cap controlling arm 60, which is fixedly mounted on an extension of the hinge pin 27, upon which the cap is fixed. The member 60 is thus adapted to act as a lever for 25 opening and closing the container as the rod 56 is moved outwardly or inwardly respectively. The rod 56 is provided with a collar 65, which is secured thereto by a set screw 66, the head of which extends through a slot 30 67 in the movable contact arm 52.

35 In operating the device, assuming the fan switch to be opened and the container top be closed, the controlling rod 56 is pulled outwardly, thus opening the top of the container and exposing the evaporating surface, and at the same time closing the fan circuit, thus creating a current of air or gas across the evaporating surface and setting in motion the cold air or gas which evaporates 40 therefrom.

45 Referring now to that embodiment of the invention illustrated in Figs. 6 and 7, the container 69 is preferably constructed with the same or a similar internal arrangement as the container shown in Fig. 1, but is made with a larger top 70, which may, if desired, be formed flat and provided with a plurality of outlet or exhaust openings 71 to permit escape of evaporated air or gas from the in-

terior of the container. The container in this embodiment of the invention is preferably provided with lugs 72, with which a bail 73, having a handle member 74, is associated for conveniently transporting the container. A neck 75 may be provided in the top of the container, through which a filling opening extends, said opening being closed by the closure member 76.

50 A plurality of dome-shaped candle closures 77 may be provided similar to the cap shown in Fig. 1, and hingedly mounted through lugs 78, provided in the top of the container.

55 Within the dome-shaped caps 77 are mounted wicks or equivalent members similar, preferably to the wick member 21, hereinabove referred to, and the caps are provided with exhaust openings 79, as before. This embodiment of the invention is particularly adapted for refrigeration purposes, having a plurality of evaporating surfaces, whereby its efficiency is increased.

60 It will be seen that a device is thus provided whose liquid air or gas supply may be replenished from time to time by removing the container 9 and inserting a full container, and that the body of liquid air or gas is conserved as much as possible by the tortuous outlet of evaporated air or gas, which helps to keep cool the liquid air or gas. The evaporation of liquid air or gas from the evaporating surface is decreased when the top is closed and increased when the top is open and the evaporating surface is exposed to the outside atmosphere.

What is claimed is:—

1. A liquid air container having an evaporating surface in capillary communication with its interior.

2. A liquid air candle comprising a container, an evaporating surface associated therewith and in capillary communication with the interior thereof, and means for regulating the extent to which said surface protrudes therefrom.

3. A liquid air candle comprising a container, an evaporating surface in capillary communication with the interior thereof, and means for covering and exposing said evaporating surface.

In testimony whereof I affix my signature.

STORY B. LADD.
